PAPER ROLL BREAKER

John A. Holmberg, Camas, Wash., assignor to
 Crown Zellerbach Corporation, San Francisco,
 Calif., a corporation of Nevada

Application August 31, 1948, Serial No. 47,069

10 Claims. (Cl. 164—84.5)

1

This invention relates to the breaking apart or separating of individual sections or small rolls after these are formed from a long roll of paper by transverse sawing or cutting through the long roll.

More specifically, this invention relates to the breaking apart of rolls of soft paper, such as rolls of toilet paper for example, after these have been cut from longer rolls.

Toilet paper, like other grades of paper, is delivered from the paper making machine in a wide strip. This paper is then wound on a long thin roller, over which cardboard cores for the finished rolls are first placed, and an elongated roll of the paper, of the diameter desired for the small finished rolls, is then produced. The elongated roll of paper is then passed through a battery of rotating saws or knives spaced an equal and desired distance apart which cut the elongated roll into small rolls of the proper size. However, in spite of the fact that these transverse cuts are made entirely through the long roll, the fibrous frayed surfaces of the opposed faces of the cuts cause the cut sections to hold together quite firmly so that the individual sections or small rolls must then be forcibly broken apart and separated before the separate small rolls can be passed to the wrapping machines.

This breaking apart and separating of the small rolls has for the most part been performed by manual labor heretofore, and the work is fatiguing and monotonous and relatively slow from the standpoint of labor costs. While some machines have been developed for the performance of this work, nevertheless, to the best of my knowledge and according to my observations they have not proven entirely satisfactory especially with extremely soft toilet tissue rolls.

The primary object of this invention is to provide an improved machine for breaking apart and separating the individual small rolls of paper after they are cut from elongated rolls.

A related object is to provide a machine of the nature above indicated, which will be simple and practical in construction, easy to operate and maintain, and in which there will be no danger of injury to the small rolls as they are broken apart and separated.

The means which I have invented and developed for accomplishing these objects, and the manner in which these objects and other advantages are attained through my invention will be briefly described with reference to the accompanying drawings.

In the drawings:

2

Fig. 1 is a plan view of my paper roll breaker; Fig. 2 is a sectional elevation on line 2—2 of Fig. 1;

Fig. 3 is a fragmentary detail illustrating in elevation the arrangement and operation of the intermittent control or the "Geneva clutch" employed in my device;

Fig. 4 is an elevation, partly in section, on line 4—4 of Fig. 1;

Fig. 5 is a perspective view of the roll-turning element of Fig. 4 showing the same separated from the rest of the machine;

Fig. 6 is a vertical section through the same element;

Fig. 7 is a fragmentary plan view, showing a slight modification in the roll-severing means; and

Fig. 8 is a sectional elevation on line 8—8 of Fig. 7.

20 Referring first to Figs. 1, 2 and 4, the sawed or cut rolls of paper, indicated by the reference character R in Fig. 1, which are to be broken apart and separated, are moved along, into, through and from the roll breaker on an endless traveling belt 10, the direction of travel being from left to right as viewed in Fig. 1. The roll breaker is operated from a single motor indicated at M in Fig. 1. The motor drives a shaft 11, through suitable gear connection, and the

30 shaft 11 carries a worm 12 which drives a worm gear 13 secured to a shaft 14 (shown in section in Fig. 2). One-half of a clutch assembly, which assembly is familiarly known as a "Geneva clutch" is secured to the shaft 14, and the other half is secured to shaft 15 rotatably mounted above shaft 14 and parallel to it. This clutch assembly is shown in Figs. 2 and 3. The lower half of the assembly includes a plate 16 having two opposite side edges 17 and 18 formed into identical concave arcs, and the plate also has two opposite ends 19 and 20 formed into convex arcs. The concave edges 17 and 18, as apparent from Fig.

2, are arcs of a circle having its center on the axis of the upper shaft 15. The convex edges 19 and 20, as apparent from Fig. 3, are arcs of a circle having its center on the axis of the lower shaft 14. A pair of elongated plates 21 are attached to opposite faces of the plate 16 and serve to support a pair of rollers 22 at opposite ends and at equal radial distance from the axis of the shaft 14.

45 The upper half of the clutch assembly consists of a plate 23 in the general shape of a Maltese cross having four identical slots 24, perpendicular to each other, adapted to accommodate

the rollers 22 of the lower half of the assembly, and having the outer edges of the four separated portions 25 formed in convex arcs corresponding to the arcs 19 and 20 of the lower assembly. From Figs. 2 and 3 it will now be apparent that with the constant rotation of the lower driven shaft 14, and therewith rotation of the plates 16 and 21 which are rigidly secured to shaft 14, there will be intermittent rotation of the upper shaft 15, and with each 180° rotation of the lower shaft there will be a 90° rotation of the upper shaft occurring during a portion of that period only.

A sprocket wheel 26 is rigidly secured on the end of shaft 15 and a sprocket chain 27 connects this wheel with a smaller sprocket wheel 28 on the end of a horizontal shaft 29 (Figs. 1, 2 and 4). Thus intermittent rotation of shaft 29 will occur as a result of constant rotation of shaft 14 and the intermittent rotation of shaft 15. The sprocket wheels 26 and 28 are of such relative size that each quarter or 90° rotation of the sprocket wheel 26 will produce a half or 180° rotation of the sprocket wheel 28.

A pair of guide walls 30 (Fig. 1) are provided for the paper rolls R as they are moved into the roll breaker on the traveling belt 10. Within the machine each entering roll R is required to move past a side guide plate 31 which is slightly out of alignment with the previous direction of travel of the rolls as illustrated in Fig. 1. A pusher plate 32 (see also Fig. 2), pivotally mounted at the lower end of a lever arm 33, is so arranged as to push the rolls sideways against the guide plate 31, and, by so doing, to force each roll individually out of alignment with the preceding rolls and thus break the rolls almost, if not completely, apart, as illustrated in Fig. 1.

The lever arm 33, on which the pusher plate 32 is carried, is pivotally mounted in a support 34 and the upper end of the arm carries a roller 38 adapted to bear against the periphery of a notched disc 35 secured on the intermittently-rotating shaft 29. A spring 36 acts to hold the roller 38 at the upper end of the arm 33 in constant contact with the disc 35. The disc 35 (Fig. 2) is formed with two similar diametrically opposite notches 37. Thus it will be apparent from Figs. 1 and 2 that when the rotation of the shaft 29, and with it disc 35, causes one of the notches 37 to be engaged by the roller 38 on the upper end of the lever arm 33, the pusher plate 32, under the pull of spring 36, will be moved outwardly or away from the paper rolls, and similarly during the time the roller 38 is in engagement with either portion of the periphery of the disc 35 between the notches 37, the pusher plate 32 will be pressed inwardly against the paper rolls as illustrated in Fig. 1.

A second stationary guide plate 39 (Fig. 1) is mounted beyond the guide plate 31 in the path of the paper rolls R. A roll-clamping plate 40, placed opposite the stationary plate 39, is movably mounted in the same manner as the pusher plate 32. Thus a notched disc 41, similar to the notched disc 35, is secured on the shaft 29 and actuates a lever arm 42 (Fig. 4) similar to the lever arm 33 and the clamping plate 40 is pivotally supported on said lever arm 42.

A bevel gear 43 (Figs. 1 and 4), secured on the shaft 29, meshes with a similar bevel gear 44 of the same size secured to the top of a vertical rotatable shaft 45 (Figs. 4, 5 and 6). The shaft 45 is rotatably supported in a sleeve 41 which is rigidly secured to a machine frame member. A

block 46 of rectangular cross section is rotatably mounted on the vertical shaft 45 between the two horizontal plates 52 and 53, the upper one 53 being firmly secured on the shaft 45 by a suitable set screw, and the lower one being secured to the machine frame and serving as a bearing plate for the bottom end of the shaft 45. A small steel ball 48 (Fig. 6), carried in a recess in the bottom face of the block 46, and held against the face of the lower plate 52 by a coil spring, prevents any inadvertent free rotation of the block 46 on the shaft 45.

Roll-carrying fingers 49 and 50 are mounted in the center of two opposite faces of the block 46 respectively and extend horizontally therefrom and perpendicular to the planes of the faces. These fingers are so positioned that they will enter the core of the paper roll when the paper roll is moved against the corresponding face of the block 46. A block-operating slide, carried by the block 46, consists of a pair of parallel rods 54 and 55, (Fig. 5), slidably mounted in a pair of horizontal parallel channels extending through the top portion of the block 46, and having their ends joined to a pair of identical bars 56 and 57. The top edges of the bars 56 and 57 extend up above the plane of the top of the plate 53 as shown in Fig. 6. Each of the bars 56 and 57 carries a lug 58 which projects inwardly from the center portion of the bar. The plate 53, secured to the vertical shaft 45, has two diametrically opposite notches 51 adapted to engage either of the lugs 58 when the corresponding bar of the block-operating slide is pushed inwardly a sufficient distance. A cam lug 59 (Figs. 5 and 6), secured to the stationary sleeve 41, is so arranged as to engage the bar 56 or the bar 57 when the block 46 is rotated, for the purpose of pushing the bar and its lug 58 outwardly and consequently causes the lug of the bar to be disengaged from a notch 51 on the plate 53. The purpose of this will be presently explained.

The operation of my roll breaker as thus far described can now be explained as follows: The 45 operation of the motor M, causing continuous rotation of the shaft 14 (Fig. 2) at reduced predetermined speed, results in intermittent 90° rotations of the shaft 15 through the intermediary of the "Geneva clutch" elements, and these intermittent rotations of the shaft 15 produce corresponding intermittent 180° rotations of the shaft 29. The notched discs 35 and 41 (Fig. 1), secured on the shaft 29, are so arranged that during the periods when the shaft 29 is not rotating one of the notches on each of the discs 35 and 41 will engage the roller at the top of the respective lever arm 33 or 42, and thus the pusher plate 32 and the clamping plate 40 will be in their outer positions. The vertical shaft 45 with its gear 44 is 50 so arranged with respect to the shaft 29 and gear 43 that when the shaft 29 is not rotating the pair of diametrically opposite notches 51 of the plate 53 will be in alignment with the direction of movement of the endless conveyor belt 10 (this direction being from left to right as viewed in Fig. 1).

During the moment in which the shaft 29 is not rotating, the rolls R, carried along on the belt 10, will move into the machine past the guide plate 31 and stationary plate 39 until the core of the first roll slides along one of the fingers, for example the finger 49, of the block 46 and pushes against one of the bars, for example the bar 56, of the block-operating slide and causes 70 the lug 58 of that bar 56 to engage the adjacent

notch of the plate 53. The shaft 29 then starts rotating. The immediate effect of the rotational movement of the shaft 29, and with it the notched discs 35 and 41 and the gear 43, is; (1) to cause the pusher plate 32 to move inwardly against the two rolls which it engages thus pushing these rolls out of alignment and making a break between the cut surfaces of these rolls as indicated in Fig. 1; (2) to cause the clamping plate 40 to move inwardly and clamp its adjacent roll against the stationary plate 39; and (3) to cause the block 46 with its fingers 49 and 50 (together with the roll on finger 49) to be rotated in unison with the plate 53 for 180° in clockwise direction (as viewed in Fig. 1). This carrying of the first roll by the finger of the block 46 completely severs all connection between the roll and the next following roll. While this first roll is being thus swung around, the clamping plate 40 will hold the next roll firmly and thus prevent any further travel of the remaining rolls until the rotating block 46 will have come to rest.

As the block 46 nears the end of its 180° rotation, the cam lug 59 on the stationary sleeve 47 engages the inside face of the bar 56 and pushes it a slight distance outwardly. This outward movement of the bar 56 brings its lug 58 out of engagement with the corresponding notch on the plate 53 and thus no further rotation of the block 46 with the plate 53 can take place until one of the lugs 58 again is pushed into engagement with one of the notches 51 on plate 53. The pushing of the bar 56 outwardly by the cam lug 59 also gives the paper roll on the finger 49 an outward shove thus aiding the roll in sliding off of the finger 49 and continuing its travel on the conveyor belt. The sliding of the roll off of the finger 49 during the 180° rotation of the block 46 is prevented by the curved outer housing wall 60 (Fig. 1).

When the shafts 29 and 45 have completed their 180° rotation they temporarily come to rest again. The clamping plate 40 and the pusher plate 32 release their holds on the rolls and the row of paper rolls R is free to advance another step to the right with the traveling belt 10 as the second roll R slides on to the finger 50 of the block 46. Then the operation is repeated. If the second roll R fails to move all the way on to the finger 50 or fails to push the block-operating slide all the way in until the lug 58 engages the adjacent notch on the plate 53 there will be no rotation of the block 46 even though the shaft 45 and plate 53 proceed with their next 180° rotation. If for any reason the first roll has failed to slide off of its finger 49 there will be no possibility of the first roll being swung another 180° around for when the block-operating slide is pushed in far enough by the second roll to cause the next rotation of the block 46 the slide will then push the first roll entirely off the finger 49 and there will be no further rotation of the block 46 until the second roll pushes the block-operating slide all the way in on the receiving side.

An automatic control switch 61 (Fig. 1) is connected with the motor M and is so arranged as to shut off the current to the motor when the supply of paper rolls to be broken ceases. The control switch 61 has a spring arm 62 which is adapted to be engaged by the rolls as they pass into the breaker, and, when so engaged, the arm 62 closes the control switch 61. Spring means (not shown) in the control switch causes the arm 62 to move into the path of the paper rolls when

not engaged by a roll and when the arm 62 moves into such position under the force of the spring, it operates to open the control switch 61 and to shut off the power to the motor M, thus preventing useless operation of the motor and parts of the machine when no rolls are passing into the breaker to be broken apart.

Figs. 7 and 8 illustrate a modification in the roll breaker as previously described which modification consists in the substitution of a modified roll-turning element in place of the block 46 with its block-operating slide. In this modified construction a block 63 is rigidly secured on the vertical shaft 45 and thus always rotates with it. The block 63 has a pair of bracket arms 64 extending from opposite vertical faces of the block 63 respectively. Each of these bracket arms is so arranged as to engage the side of a roll R as it is moved up against the face of the block 63 while the block temporarily is stationary. Then as the block starts rotating the engaging bracket arm 64 will swing the roll out to one side. The roll continues its outward swing after its initial push or kick by the bracket arm until it slides outwardly out of engagement with the bracket arm and comes into contact with the guide wall 65 of the housing. Then the roll continues its travel on the conveyor belt 10. With this simplified arrangement and construction of the roll-turning block I make the conveyor belt 10 wider or else provide a second conveyor belt to carry the roll along after it has been swung or kicked out of its previous path by a bracket arm of the block 63. In all other respects my roll-breaker in this modified form is similar in construction and operation to that which was first described.

It would be possible to make minor changes within the scope of my invention in the roll breaker which I have illustrated and described. Thus, for example, other means could be employed for producing the intermittent rotation of the shaft 29. However, my invention in the forms which I have illustrated has provided very satisfactory in actual operation over a period of several months, and the roll moving blocks and associated elements have operated successfully when made in either of the ways I have described.

I claim:

1. In a roll breaker of the character described, means for moving paper rolls through said breaker, a roll-moving element mounted for rotation on an axis and located in the path of said moving means, means for producing intermittent partial rotations of said element, a roll-engaging member mounted on said element, a pusher plate for temporarily pushing individual rolls out of alignment upon their entry into said breaker, whereby to start the breaking apart of the separate rolls, means for intermittently operating said pusher plate, and a roll-holding clamp for preventing travel of subsequent rolls in said breaker while one roll is being moved by said element.
2. In a roll breaker of the character described, a roll-moving element mounted for rotation on a vertical axis, means for producing intermittent partial rotations of said element, roll-engaging members mounted on said element, a pusher plate for temporarily pushing individual rolls out of alignment upon their entry into said breaker, whereby to start the breaking apart of the separate rolls, means connected with said element rotating means for operating said pusher plate, a roll-holding clamp for preventing travel of sub-

sequent rolls in said breaker while one roll is being moved by said element, and means for operating said clamp connected with said element rotating means.

3. In a roll breaker of the character described, means for moving paper rolls through said breaker, a roll-moving block mounted for rotation on a vertical axis and located in the path of said moving means, means for producing intermittent 180° rotations of said block, roll-engaging members mounted on opposite faces of said block respectively, a pusher plate for temporarily pushing individual rolls out of alignment upon their entry into said breaker, whereby to start the breaking apart of the separate rolls, means connected with said shaft rotating means for operating said pusher plate, a roll-holding clamp for preventing travel of subsequent rolls in said breaker while one roll is being turned by said block, and means for operating said clamp connected with said block rotating means.

4. In a roll breaker of the character described, a roll-turning element mounted for rotation on a shaft, means for producing intermittent 180° rotations of said shaft, roll-engaging members mounted on said element, shaft-engaging means operated by the movement of a paper roll into contact with said element and serving to cause said element temporarily to be rotated with said shaft, whereby said element and the roll will be given a 180° rotation, and a roll-holding clamp for preventing travel of subsequent rolls in said breaker while one roll is being turned by said element.

5. In a roll breaker of the character described, a roll-turning element mounted for rotation on a vertical shaft, means for producing intermittent 180° rotations of said shaft, roll-engaging members mounted on opposite faces of said element respectively, shaft-engaging means carried by said element and actuated by the movement of a paper roll into contact with said latter mentioned means whereby to cause said element to be rotated with said shaft, whereby said element and the roll will be given a 180° rotation, a roll-holding clamp for preventing travel of subsequent rolls in said breaker while one roll is being turned by said element, and means for intermittently operating said clamp connected with said shaft rotating means.

6. In a roll breaker of the character described, a roll-turning block mounted for rotation on a vertical shaft, means for producing intermittent 180° rotations of said shaft, a pair of roll-carrying fingers mounted on opposite faces of said block respectively, a shaft-engaging element carried by said block and operated by the movement of a paper roll into contact with said element and serving to cause said block temporarily to be rotated with said shaft, whereby said block and the roll will be given a 180° rotation, a pusher plate for temporarily pushing individual rolls out of alignment upon their entry into said breaker, whereby to start the breaking apart of the separate rolls, a roll-holding clamp for preventing travel of subsequent rolls in said breaker while one roll is being turned by said block, and means for operating said clamp connected with said shaft rotating means.

7. In a roll breaker of the character described, a roll-turning block mounted for rotation on a vertical shaft, means for producing intermittent 180° rotations of said shaft, a pair of roll-carrying fingers mounted on opposite faces of said block respectively, a shaft engaging slide carried by said block and operated by the movement of

75 a paper roll into contact with said slide and serving to cause said block to be rotated with said shaft, whereby said block and the roll will be given a 180° rotation, a pusher plate for temporarily pushing individual rolls out of alignment upon their entry into said breaker, whereby to start the breaking apart of the separate rolls, means connected with said shaft rotating means for operating said pusher plate, a roll-holding clamp for preventing travel of subsequent rolls in said breaker while one roll is being turned by said block, and means for operating said clamp connected with said shaft rotating means.

8. A roll breaker including means for moving paper rolls through said breaker, a roll-moving block mounted for rotation on a vertical axis and located in the path of said moving means, means for producing intermittent partial rotations of said block, roll-engaging members mounted on said block, a pusher plate for temporarily pushing individual rolls out of alignment upon their entry into said breaker, whereby to start the breaking apart of the separate rolls, means connected with said block rotating means for intermittently operating said pusher plate, and a roll-holding clamp for preventing travel of subsequent rolls in said breaker while one roll is being moved by said block.

9. A roll breaker including means for moving paper rolls through said breaker, a roll-turning block mounted on a vertical shaft and located in the path of said moving means, means for producing intermittent 180° rotations of said shaft, a pair of roll-carrying fingers mounted on opposite faces of said block respectively, a block-operating slide carried by said block operated by the movement of a paper roll into contact with said slide and serving to cause said block temporarily to be rotated with said shaft, whereby said block and the roll will be given a 180° rotation, a roll-holding clamp for preventing travel of subsequent rolls in said breaker while one roll is being turned by said block, and means for intermittently operating said clamp connected with said shaft rotating means.

10. A roll breaker of the character described comprising means for moving paper rolls through said breaker, a roll-turning block mounted on a vertical shaft and located in the path of said moving means, means for producing intermittent 180° rotations of said shaft, a pair of roll-carrying fingers mounted on opposite faces of said block respectively, a shaft-engaging slide carried by said block actuated by the movement of a paper roll into contact with said slide and serving to cause said block temporarily to be rotated with said shaft, a fixed slide-moving member disconnecting said slide from said shaft at the end of each 180° rotation of said block, whereby the pushing of said slide by a paper roll will cause said block and the roll to be given a 180° rotation by said shaft, a pusher plate for temporarily pushing individual rolls out of alignment upon their entry into said breaker, whereby to start the breaking apart of the separate rolls, means for intermittently operating said pusher plate, a roll-holding clamp for preventing travel of subsequent rolls in said breaker while one roll is being turned by said block, and means for operating said clamp connected with said shaft rotating means.

JOHN A. HOLMBERG.
